POLARITY CHANGER

Robert H. Lee, Indianapolis, Ind., assignor, by
mesne assignments, to Cornell-Dubilier Elec-
tric Corporation, South Plainfield, N. J., a cor-
poration of Delaware

Application October 9, 1946, Serial No. 702,125

2 Claims. (CL 321—49)

1

My present invention relates in general to elec-
trical regulating systems and more particularly to
vibrator operated regulating systems.

An object of my invention is the provision of a
vibrator converter system for converting a direct
current into alternating current, wherein there is
provided a pair of vibrating contacts operating in
series for the alternate changing of the polarity
of a direct current system, in which means are
provided for increasing the operative efficiency
and particularly the life of the contact points
of the vibrating interrupter.

For the purpose of disclosing my invention, I
have illustrated an embodiment thereof, in
which:

Fig. 1 is a diagrammatic view of a circuit ar-
rangement embodying my invention;

Fig. 2 is a side elevation of a type of vibrator
which may be used with my invention; and

Fig. 3 is an end elevation of the vibrating reeds.

I have illustrated in Fig. 1 a vibrating inter-
rupter which is adapted to reverse the polarity of
a direct current supply from direct current sup-
ply leads 2 and 3 through primary windings 12
and 13 of a suitable transformer, the secondary
windings 14 and 15 of which are adapted to be
connected to a load 16.

The vibrator 1 is provided with a pair of vibra-
tory reeds 4 and 5 mechanically connected to op-
erate in unison, but electrically divorced from one
another. The vibrating reed 4 operates between
a pair of relatively stationary contacts 8 and 9.
The vibratory reed 5 operates between a pair of
relatively stationary contacts 10 and 11. The
reed 4 is connected to one side 3 of the direct
current supply line and the reed 5 is connected to
the opposite side 2 of the direct current sup-
ply line. The reeds are driven in unison through
the medium of a driving magnet having a driving
coil 6, one terminal of which is connected to one
side 2 of the supply line and the opposite ter-
minal of which is connected to the relatively sta-
tionary contact 7 adapted to be intermittently en-
gaged by the vibratory reed 4. The arrangement
is such that upon the closing of the main supply
switch (not shown), a driving circuit will be es-
tablished through the coil 6, which however, will,
as soon as the reed 4 is moved away from the
contact, have its circuit interrupted to immedi-
ately be reestablished by the back swing of the
vibrating reed 4.

The contacts 8 and 10 of the two vibratory
members are connected to one terminal of the
primary winding 13 of a transformer. The con-
tacts 8 and 11 are connected to the opposite

2

terminal of the primary winding 12 of the trans-
former. The two inner terminals of the windings
12 and 13 are connected to the opposite sides
3 and 2 of the supply lines, respectively through
condensers 17 and 18. Therefore, as the reeds
are vibrated to alternately close the circuit
through the contacts 8 and 11 and then the con-
tacts 8 and 10, the current will flow through the
primary windings 12 and 13 of the transformer
in the opposite directions.

During the normal operation of the vibrator
interrupter, the reeds 4 and 5 will so operate that
they will simultaneously make and break con-
tact with their respective stationary contacts.

However, there are occasions when through some
cause of another, the reeds will not be operating
in absolute synchronism, and accordingly, the
make and break of one of a pair of contacts may
be just ahead of the other of the pair of contacts,
resulting in a heavy and destructive arc across
the contacts last to break. In order to avoid this
condition, I provide by-pass paths including the
condensers 17 and 18 and the windings 12 and
13, so that the current may be divided and the
last contacts to break are only carrying the load
of one of the primary windings 12 and 13.

During the contact engaging period of the vi-
brator 1, the transformer side of the condensers 17
and 18 are at a potential midway between that
provided by the power source. At the instant of
disengagement or breaking of the contacts one
of the two contacts, which are in series in the
vibrator circuit, will always break before the
other, unless the vibratory reeds 4 and 5 are
operating in absolute synchronism. The con-
tact which breaks first must break only the volt-
age present between its side of the direct current
line and the transformer side of the condenser
17 and 18 or half of the supply voltage. Current
flow is allowed to continue through the other
contact which is still engaged through the pri-
mary winding to which it is connected and
through the condensers 17 and 18. It is there-
fore apparent that as a result of the above ar-
rangement, the heavy arcing of the last to break
contact is materially reduced. While the vibra-
ting reeds are mechanically connected to operate
in unison, I have found from experience that it is,
from a practical and commercial standpoint,
practically impossible to effect the make and
break contact of the reeds in absolute synchro-
nism.

In Figs. 2 and 3, I have illustrated a vibratory
interrupter which may be conveniently used in
connection with the circuit illustrated in Fig. 1.

In this structure, I provide a pair of vibratory reeds 21 and 22 which are mechanically connected together so as to operate as a single unit through the medium of an insulating crosspiece 23 having its ends riveted, the reed 21 being provided with a weighted armature 24 and the reed 22 having a weighted armature 25. The reed 21 is secured to the crosspiece 23 and to its armature 24 through the medium of a rivet 26 and the reed 22 is likewise riveted to the crosspiece 23 and its armature 25 through the medium of the rivet 27. One of the reeds carries a flexible arm 28 carrying a suitable contact and forming the driver contact controlling the magnet of the vibrator. This contact arm 28 is adapted to engage with a relatively stationary contact 29. The reed 21 vibrates between a pair of relatively stationary contact carrying arms 30 and 31 and the reed 22 vibrates between a pair of corresponding relatively stationary contact carrying arms. The arms 30 and 31 carry respectively contacts 32 and 33 which are respectively adapted to be engaged by the contacts 33 and 34 carried on fingers supported on the reed 21. A similar arrangement is provided for the reed 22. The reeds are driven through an electromagnet having a polepiece 35 off center with respect to the armatures 24 and 25, which polepiece is surrounded by a winding 37 secured in a U-shaped frame 38. This frame is secured between the outer ends of a pair of side members 39 and 40 and at the opposite end, the reeds and fingers are supported between suitable insulating spacer blocks 41 interposed between the side members and secured therein by suitable bolts or rivets.

Due to the fact that the two reeds 22 are connected by the insulating member 23, the reeds are mechanically connected to operate in unison, but electrically divorced from one another.

I claim as my invention:

1. An electrical system for converting current from a direct current source into alternating current and supplying the latter to a load, which system comprises a vibratory circuit including a transformer and two vibratory interrupters, each having oppositely disposed contact means and a vibratory contact means operating therebetween, a transformer having a primary winding, two

corresponding contacts of the oppositely disposed contacts of the interrupters being connected in series with one terminal of said primary winding and the other corresponding contacts of the oppositely disposed contacts of the interrupters being connected to the opposite terminal of said primary winding and a current diverting circuit for each of said oppositely disposed contacts, connecting said contact with one side of the direct current source through at least a portion of said primary winding and a condenser.

2. An electrical system for converting current from a direct current source into alternating current and supplying the latter to a load, said system comprising a vibratory circuit including a transformer having a primary winding comprising two coils connected in series and two vibratory interrupters, each having oppositely disposed contact means and a vibratory contact means operating therebetween, corresponding contacts of the oppositely disposed contacts of the interrupters being connected in series with one terminal of said primary winding of the transformer and the other corresponding contacts of the oppositely disposed contacts of the interrupter being connected to the opposite terminal of said primary winding, a center tap between the two coils of said transformer, a circuit connection between each of said direct current supply lines and said center tap, and a condenser connected in each of said circuit connections.
